UNITED STATES PATENT OFFICE.

HENRY L. DE ZENG, OF PHILADELPHIA, PENNSYLVANIA.

NOSE-PIECE FOR EYEGLASSES.

No. 842,181.

Specification of Letters Patent.

Patented Jan. 29, 1907.

Application filed January 7, 1905. Serial No. 239,999.

To all whom it may concern:

Be it known that I, HENRY L. DE ZENG, a citizen of the United States, residing in the city and county of Philadelphia, State of Pennsylvania, have invented a new and useful Nose-Piece for Eyeglasses, of which the following is a specification.

My invention relates to an improvement in nose-pieces for eyeglasses; and it consists in forming such pieces or the facings thereof of foraminous material, whereby said pieces will take effective hold of the nose without severity of action thereon.

Figure 1 represents a rear elevation of an eyeglass embodying my invention. Fig. 2 represents a section thereof on line *x x*, Fig. 1. Fig. 3 represents the form of facing employed.

Similar letters of reference indicate corresponding parts in the figures.

Referring to the drawings, A designates an eyeglass which, excepting the feature of my invention applied thereto, is of usual construction. B designates the nose-piece thereof, the same having its facing on nose-contacting surfaces formed of foraminous material.

In Fig. 3 the facing C is finely-reticulated material, producing a series of meshes, it being seen that when the facings are adjusted on the nose the walls of the openings numerously take hold of the nose, owing to the tendency of the skin to enter said openings in the manner of interlocking, thus firmly retaining the glass on the nose without liability of the same to shift or drop even should the skin be moist from perspiration or otherwise slippery. Again, the numerous openings in the facing permit the excretions of the skin to be evaporated through the same, and thus avoid collection or deposits beneath the bearing or contact surfaces,

which would otherwise serve as lubricants, causing the guard to shift.

The facing, Fig. 3, may be secured to the frame E of a nose-piece, as shown in Fig. 2, or by other suitable means. The attaching-arm may or may not be integral with the said frame E or the perforated plate which comprises the facing D.

Various changes may be made in the details of construction shown without departing from the general spirit of my invention, and I do not, therefore, desire to be limited in each case to the same.

In addition to the advantages which my invention offers in the way of being a nose-guard which will hold firmly to the nose it can, owing to its mechanical construction, be bent and formed to the contour of the nose by the use of pliers without denting or otherwise impairing its bearing-surface upon the nose.

Having thus described my invention, what I claim as new, and desire to secure by Letters Patent, is—

1. An eyeglass guard or nose-piece having an open supporting-frame and a wire mesh or netting fixed flatly upon the face thereof substantially as described.

2. An eyeglass guard or nose-piece comprising an open-frame backing faced with a wire gauze or netting, the said facing lying in a plane or planes parallel with the said backing.

3. An eyeglass guard or nose-piece comprising an open supporting-frame, a connecting-arm and a flat facing of wire-cloth substantially as described.

HENRY L. DE ZENG.
